UNITED STATES PATENT OFFICE

2,181,997

DEVICE FOR THE FABRICATION OF
NECKTIES

Morris S. Malek, Ridgefield, N. J.

Original application December 24, 1935, Serial No.
55,970. Divided and this application February
12, 1938, Serial No. 190,174

5 Claims. (Cl. 112—2)

This invention relates to new and useful improvements in devices for the fabrication of neckties, this being a division of my application filed on December 24, 1935, Serial No. 55,970 which matured into Patent No. 2,110,996 on March 15, 1938.

It is primarily within the contemplation of this invention to enable the linings and outer materials of neckties to be conveniently held together during the sewing or stitching operation. And in this aspect of my invention a pair of flexible clamping strips is employed to adjustably clamp therebetween the lining and covering material of the necktie, the object being to enable 10 such combination to be operatively associated with the instrumentalities of a sewing machine for manipulating and feeding the necktie material during the stitching operation.

The invention contains the provision of means 20 for assisting in the folding of the necktie covering material, and an arrangement for holding and retaining the folded necktie within the above-referred-to clamping strips, for operative manipulation, these being further objectives of my invention.

It is a further object of this invention to enable the lining and necktie covering material to be sewed together without removing the parts from the clamping strips, and to enable the sewing 30 operation to be efficiently and conveniently performed.

It is also within the contemplation of this invention to enable the sewing and stitching operations to be performed within a minimum of 35 space, and by means of a device of simple and economical construction.

Other objects, features and advantages will appear from the drawings and the description hereinafter given.

40 In the drawings,

Figure 1 is a perspective view of a device constructed according to this invention and adapted to assist in the manufacture of neckties.

Figure 1A is a perspective view of the top clamping strip in a position above the bottom clamping strip which is shown in Figure 1.

Figure 2 is a transverse sectional view taken on the line 2—2 of Figure 1.

Figure 3 is a fragmentary sectional view taken 50 on the line 3—3 of Figure 1.

Figure 4 is a plan view of the device shown in Figure 1 but illustrated with the parts in a different position.

Figure 5 is a fragmentary enlarged detailed 55 view of a portion of Figure 4.

Figure 6 is a fragmentary enlarged sectional view taken on the line 6—6 of Figure 4.

Figure 7 is a plan view of a sewing machine with an attachment to facilitate the sewing of the ties according to this invention, a rack to 5 supply the ties being also illustrated in this view in its proper relation to the sewing machine.

Figure 8 is an elevational view of a portion of Figure 7 looking in the direction of the line 8—8 of Figure 7.

Figure 9 is a side elevational view of Figure 8 looking in the direction of the arrows 9—9.

Figure 10 is a fragmentary enlarged sectional view taken on the line 10—10 of Figure 7.

Figure 11 is a sectional view taken on the line 15 11—11 of Figure 10.

Figure 12 is a sectional view taken on the line 12—12 of Figure 7.

The apparatus by which the instant method of manufacturing ties is carried out includes a 20 table 10 with which there is associated a pair of flexible clamping strips 11 and 12. These strips are adapted to clamp the lining and the covering material of a necktie. A means is provided which is mounted on the table and is adapted for 25 removably holding the lower of said clamping strips in a certain position upon the table so that the parts of the necktie may be properly positioned relative to each other as hereinafter further described. In conjunction with the holding 30 means there is a means for clamping the flexible strips 11 and 12 together. This means is shown to comprise headed fastening pegs 13 on the lower clamping strip 11 adapted to coact with openings 14 and 14' in member on the top clamping strip 35 12. The opening 14 is circular and a tight fit on the central peg 13, while the openings 14' are elongated so that the end pegs 13 may move.

A lining guide gauge 15 is movably mounted on the table and is adapted to be placed on the lower 40 clamp strip 11 when the said clamp strips are separating so that the lining material may be placed thereagainst. On the drawings the lining material is indicated by reference numeral 16 (see Figure 6) and note that one edge thereof 45 is in contact with the gauge. This lining material may be of one piece or of two sections as is customary in the construction of a tie lining. If of two sections they are treated just as though they were one, that is they are placed in relatively correct positions to each other and then placed against the gauge. A tie covering material guide gauge 17 is also movably mounted on the table and is adapted to be placed upon the lining material (see Figure 6) to hold the same, and 50 /

also is adapted to guide the placing of the tie covering material 18 thereagainst and properly upon the lining.

- 5 Holding strips 19^a and 19^b are adapted to be placed over the tie covering material and the lining to hold these parts while they are being bent. A mechanism is provided for bending the tie covering material over the lining and consists essentially of a plate 20 which is slidably mounted on 10 the table and has its forward edge 20' normally disposed beneath the tie covering material so that when moved forwards it is adapted to bend this material. The holding strips 19^a and 19^b are adapted to be withdrawn after the tie covering material is bent over the lining. The said clamping strips 11 and 12 are then adapted to be connected together by the fastening pegs 13 and openings 14 and 14' to hold the lining and tie covering material in a position ready to be sewn.
- 20 The ends of the clamping strip 11 have small transverse strips 11^d rigidly connected therewith, which in turn, support inwardly overhanging tubular members 11^e. Preferably, these tubular members are square in transverse cross section.
- 25 The ends of the clamping strip 12 have rigidly mounted thereon the strips 23 which, when the strip 12 is flexed downwardly, may slide beneath the overhanging tubular members 11^e, as clearly shown in Figure 3, to hold these parts together.
- 30 The strip 12 is flexible so that the sliding is possible in bowed condition and is not interrupted by the fastening elements 13. When in the proper position the fastening elements 13 may engage through the openings 14 and 14'.
- 35 The central fastening element 13 engages in the circular opening 14 which holds the clamp strip 11 at the center relatively fixed to the clamping strip 12. The openings 14' are slots so that the clamping strips may be flexed to arcuate 40 positions, as shown in Figures 7 and 8. When thus flexed, the inner clamping strip 12 tends to tightly engage against the outer clamping strip 11 and so tightly clamp the necktie parts in position ready to be sewn as hereinafter further described.
- 45 The means for releasably holding the lower clamping strip 11 in position comprises a pair of arms 21^a and 21^b which are pivotally supported at their rear ends by standards 22 mounted upon the table. The tubular members 11^e of the bottom clamping strip 11 may slidably engage upon the arms 21^a and 21^b so that the lower clamping strip 11 is pivotal and may assume a predetermined position resting upon the table top. The 55 clamping strip 11 may be slipped into position and removed from position when desired.
- 50 The lining guide gauge 15 comprises a strip 15^a, preferably of rubber or other resilient material having its outer face properly shaped to guide the placing of the lining 16 thereagainst. This strip 15^a is attached upon a rigid bar 15^b which is supported at its end upon arms 15^c. These arms are hingedly connected by hinges 15^d to the top of the table 10.
- 60 The tie covering material gauge 17 comprises a resilient strip of material 17^a which is supported in a channel shaped rigid strip 17^b supported at its ends by arms 17^c. These arms are connected by hinges 17^d with the table top 10.
- 65 The holding strips 19^a and 19^b are attached at their outer ends upon the heads 25 of T-shaped members 26. These T-shaped members have their bodies engaging in dovetailed slots in the table top 10 (see Figure 2). The arrangement 70 is such that the T-shaped members 26 may be

75 moved to the extended positions shown in Figure 1 in which the holding strips 19^a and 19^b are inoperative. Or, these T-shaped members may be retracted so that the holding strips are engaged over the tie materials. The T-shaped members 26 are readily retractable by a spring turned gear 50 which meshes with racks 51 and 52 on opposite sides thereof, said racks being connected with the said members 26. More particularly, the gear 50 is connected with a drum 52' upon which a 10 spring 53 is mounted. This spring acts between the stationary table top 10 and the drum for normally urging the drum into a neutral position. A cable 55 is wound upon the bottom portion of the drum 52' by which the drum may be manually turned when desired to move the T-shaped members 26 together.

15 The racks 51 and 52 are slidably supported on tracks 56 mounted upon the bottom of the table top 10. Pins 57, as shown in Figure 4, extend 20 upwards from in-turned ends of the racks 51 and 52 and connect with the slidable members 26. The cable 55 is carried over several pulleys 58 and extends downwards and connects with the front end of a foot pedal 59 which is pivotally mounted 25 by a hinge 70 at its rear. The spring 57 normally urges the members 26 into extended positions, as shown in Figure 1, and raises the pedal 59. The pedal may be manually depressed for moving the members 26 inwards to the position shown in Figure 4.

30 The means for bending the tie covering material over the lining and over the holding strips 19^a and 19^b comprises a plate 20 which has a 35 pair of parallel strips 33 attached upon the bottom side thereof. These parallel strips 33 engage in a pair of parallel grooves 34 in the table top. A handle 35 upon the plate 20 is used to manually move the plate. This plate 20 is held in a raised position from the table top 10 by a stationary 40 plate 36 which rests upon the table top. The plate 20 rests upon the plate 36. The arrangement is such that the plate 20 may be moved forwards to bend the tie material as hereinafter 45 more fully explained.

50 The lining guide gauge 15 is urged into an operative position or an inoperative position by springs 15^f. These springs extend through openings 15^g in the table top. At the top ends the springs 15^f connect slightly above the pivot points 55 of the arms 15^c. At the bottom ends these springs 15^f connect with brackets 15^h mounted upon the bottom of the table top 10. The points of connection of the springs 15^f are such that normally when the gauge 15 is raised the springs 55 act past the dead center and hold the gauge in open position, and when the gauge is manually lowered the springs assume the position shown by the dot and dash lines 15ⁱⁱ in Figure 2 so as to urge the gauge downwards into closed position.

55 The device so far described may be better understood by considering its operation. Figure 1 shows the parts in operative positions in which a lining of a necktie may be placed upon the bottom clamping strip 11. This lining may be correctly placed upon the clamping strip 11 by first lowering the lining guide gauge 15. In Figure 6, the lining guide gauge is shown in the operative position resting on the plate 10. The lining is placed so that one of its edges is in intimate contact with the side face of the resilient portion 15^a of the lining guide gauge. The tie covering material gauge 17 is then moved to the lowered positions, as shown in Figure 6, in which it serves to hold the lining 16 which furthermore serves to 70

constitute a guide for the edge of the tie covering material. The tie covering material 18 is placed in position with its edges against the said edge of the strip 17^a. The holding strips 19^a and 19^b are moved into positions over the lining and the tie covering materials, as shown in Figure 4 by pressing downwards on the pedal 59. The folding plate 20 is moved forwards so as to fold over the tie covering material 18 on the holding strips 19^a and 19^b as clearly shown in Figure 6. With the plate 20^a in this position so as to hold the bent tie material, the holding strips 19^a and 19^b are drawn out by releasing the pedal 59.

The flexible clamping strip 12 is then placed in position upon the clamping strip and secured thereby by the proper inter-engagement of the fastening pegs 13 and the openings 14 and 14'. The connected clamping strips and the tie materials clamped thereby are removed from the arms 21^a and 21^b and the tie is ready to be sewn. Preferably, one operator should produce these holding devices and store them on a suitable rack so that another operator may perform the sewing operation.

25 In Figures 7 to 9 inclusive the sewing of the ties by the use of these holding devices is shown. A conventional sewing machine 40 is mounted upon a support plate 41 upon which there is also mounted a bracket 42. This bracket 42 supports a tubular bearing 43 in which a stud shaft 44 turns. This stud shaft is adjustably connected by a wing clamp screw 45 with a bushing 46 attached on the center of a transverse support bar 47. This transverse support bar is 30 equipped with transverse sockets 48 which are adapted to be engaged by pins 48^a in the tubular members 11^a of the clamping strip 11 for the purpose of holding the clamping strips in arcuate shape as clearly shown in Figures 7 and 8. A 35 plurality of bars 47' are adapted to rest on a spaced pair of tracks 49, and are perforated to receive the pins 48^a of the sockets 48 so that the tie holding devices may be stored to be ready to be sewn when desired.

40 A radial arm 60 is connected with the shaft 44 and is provided with a weight 61 adjustable thereon. This arm and weight acts as a counter-weight so that the arcuate shaped clamping strips may be swung around when desired. The sewing machine 40 is so mounted upon the support 41 that when the tie holding device is engaged upon the bracket 42 the tie held thereby is in position ready to be sewn. It is then merely necessary to pivot the arcuate tie holding support so that the sewing is begun at one end of the tie material and terminated at the other end. The dot and dash lines in Figure 8 show another position of pivoting of the parts.

45 A U-shaped holding element 62 is mounted on the end of a rod 63 which is slidable in a tubular member 64 mounted upon the top of the bracket 42. A lever 65 is pivoted intermediately at 66 upon the bracket and has its inner end connected with the bar 63 through a slot in the tubular member 64 by which the bar 63 may be extended when desired. When the U-shaped member 62 engages the bar 47 the particular tie holding device is held against pivoting. When the operator wishes to sew the tie he moves the lever 65 to release the U-shaped bracket 62 from the bar 47. The purpose of the wing screw 45 is to permit a proper relative adjustment upon the shaft 44 so that the arcuate shaped tie holding device is in proper position relative to the sewing machine.

50 While I have illustrated and described the pre-

ferred embodiment of my invention, it is to be understood that I do not limit myself to the precise construction herein disclosed and the right is reserved to all changes and modifications coming within the scope of the invention as defined in the appended claims.

What I claim is:

1. In a device for folding and holding tie material, the combination of a lower clamping strip of flexible material, an upper clamping strip of flexible material, cooperative fastening means in the region of the end portions of said strips, said fastening means fitting loosely together to permit relative end movement of the clamping strips in a direction longitudinal of the strips, whereby the pair of clamping strips may be flexed to arcuate shape.

2. The combination according to claim 1 for use in a sewing machine having a sewing surface and a predetermined direction of material feed, wherein the said sewing machine is provided with a cross bar pivotally mounted to turn on an axis located in a plane parallel to the said sewing surface and normal to the said direction of feed and provided at each end with securing means and wherein one of the said pair of clamping strips is provided with means engageable with the said securing means of the cross bar to mount the said pair of clamping strips in the cross bar and hold them in arcuate shape, whereby the said pair of clamping strips may be turned to feed the tie material past the said sewing surface.

3. In a device for folding and holding tie material, the combination of a lower clamping strip provided with fastening means, an upper clamping strip provided with fastening means cooperative with the said fastening means of the lower clamping strip, the said clamping strips being formed of flexible material and the said fastening means comprising a plurality of cooperative fasteners spaced along the length of the respective clamping strips, the fasteners provided centrally of the strips fitting snugly together and the end fasteners fitting loosely together to permit relative end movement of the clamping strips, whereby the pair of clamping strips may be flexed to arcuate shape.

4. In a device for folding and holding tie material, the combination according to claim 3 wherein the fastening means on one of said clamping strips comprises a plurality of spaced pegs, and the fastening means on the other clamping strip comprises a correspondingly spaced plurality of apertures adapted to operatively receive said pegs, all the said apertures not in the region of the center of the strip being sufficiently elongated to permit a movement of the pegs therein upon an operative flexing of the clamping strips.

5. In a device for folding and holding tie material, the combination of a lower clamping strip of flexible material, an upper clamping strip of flexible material, cooperative fastening means in the region of the end portions of said strips, said fastening means fitting loosely together to permit relative end movement of the clamping strips in a direction longitudinal of the strips whereby the pair of clamping strips may be flexed to arcuate shape; the ends of one of said clamping strips being provided with securing means, and supporting means for said clamping strips engageable with said securing means for holding said strips in flexed and arcuate condition for use in a sewing machine.

MORRIS S. MALEK.
